UNITED STATES PATENT OFFICE

ALEXANDER W. PORTER, OF ATLANTIC CITY, NEW JERSEY

DESIGN FOR A BUILDING FRONT

Application filed November 25, 1932. Serial No. 46,153. Term of patent 14 years.

To all whom it may concern:

Be it known that I, ALEXANDER W. PORTER, a citizen of the United States, residing at Atlantic City, in the county of Atlantic and State of New Jersey, have invented a new, original, and ornamental Design for a Building Front, of which the following is a specification, reference being had to the accompanying drawing, forming part thereof.

Figure 1 is a view in front elevation of a building front, showing my new design.

Figure 2 is a view in side elevation thereof shown to a somewhat reduced scale.

I claim:

The ornamental design for a building front as shown.

ALEXANDER W. PORTER.
